WIRE CONNECTER

Filed Oct. 18, 1928

Inventor
Robert A. Becker.

By his Attorney
John J. Thompson

UNITED STATES PATENT OFFICE

ROBERT A. BECKER, OF POUGHKEEPSIE, NEW YORK

WIRE CONNECTER

Application filed October 18, 1928. Serial No. 313,286.

This invention relates to a connector for securing the meeting end of wires, cables or rods together to form a strong mechanical and electrical joint, such as employed by power, light and signal installation, where it is desired to secure together the ends of two single wires, the ends of stranded cables, or the ends of rods, in a quick, strong and adjustable manner without twisting together, or by the use of solder, or welding.

The object of the invention is to provide a connector containing few parts, simple of construction and application; strong, and having a maximum grip upon the wire, thus providing a connector having low electrical resistance.

Another object being to provide a connector, in which the usual nuts are not employed, thus doing away with the objection to splitting of nuts, tearing of threads and the like.

Still another object being to provide a connector having a long grip upon the wire, thus having a large surface contact insuring good electrical contact.

Also providing means whereby one wire may be secured at a time without having to secure both of the ends at the same time, thus allowing of the device being assembled to one wire or other article, before being attached to the end of the other wire.

With these and other objects in view, the invention consists in certain combination and construction of parts as will hereinafter be fully described and claimed, and also illustrated in the accompanying drawings, in which like figures of reference refer to corresponding parts in all of the views, but it is to be understood that slight changes may be made without departing from the spirit of the invention.

In the drawings:

Figure 1 is a side elevation of the connector, showing the same as applied to the ends of two meeting wires.

Figure 2 shows a group view of the several parts which go to make up the device.

Figure 3 shows a longitudinal sectional

view of the connector, illustrating the clamping means.

Figure 4 shows an end view of the device.

Figure 5 shows a cross sectional view taken on the line A—A of Figure 1. 55

Figure 6 shows an end view of the body portion without the threaded plug.

Referring to the drawings, the device comprises a body portion 10, here shown as being made from hexagonal material such as brass, but which may be of any suitable shape in cross section and of any suitable material. 60

Said body portion 10, is formed with an axial bore extending its entire length, but being tapered outward toward each end as shown by the numeral 11, the ends of said tapered portions being provided with the internal threads 12. 65

Within each of said ends of the body portion 10, is secured a wire gripping plug 13, which is formed with an axial bore 14 slightly larger than the wire 15, so that it may easily be placed upon the end of the wire. 70

Said gripping plug comprises a body provided with the threads 16 adapted to engage the threaded ends 12; a head integral therewith and provided with flats 17 for the engagement of a wrench or other means of operating, and a tapered nose portion 18, of the same taper as the internal taper of the ends of the body portion 10; said tapered nose 18 being rendered resilient by a series of longitudinal slots or saw cuts 19, so that as said plug is screwed into the end of the body portion 10, the tapered nose will be closed in on the wire 15 to grip and hold the same against removal. 80

It will be thus be seen that the wire may be inserted or removed from the connector by slightly backing out the plug to relieve the grip of the tapered nose, and also as the nose or gripping collet can be long owing to this construction, a long grip is effected 85 on the wire, yet the entire device is compact, and there are no loose bushing, or nuts.

Having thus described my invention, what I claim as new and desire to secure by Letters Patent, is:

A wire connector of the class described, comprising a hexagonal body portion formed with an axial bore having a short portion of slightly larger diameter than the wire, an enlarged and threaded opening in the ends of said body portion, a tapered portion connecting said bore with said threaded ends, a clamping plug formed with an axial bore, a threaded body adapted to coact with the threaded ends of the body portion, a tapered and slotted end formed thereon adapted to coact with the tapered portion of the body bore to grip the wire, and hexagonal heads formed on the outer end of the plugs.

In testimony whereof I affix my signature.
ROBERT A. BECKER.
